UNITED STATES PATENT OFFICE.

CESARE BARBIERI, OF NEW YORK, N. Y., ASSIGNOR TO THE VORTEX MFG. CO.,
OF CHICAGO, ILLINOIS, A CORPORATION OF ILLINOIS.

FOLDING PAPER CUP.

Application filed July 3, 1922. Serial No. 572,522.

This invention relates to a type of paper cup which when stored or packed is adapted to be folded into a flat form but when in use is rounded into a conical form.

5 It is an object of this invention to provide a flat paper cup which can be opened out into a conical cup with less pressure than has heretofore been required.

10 It is a further object of this invention to provide a flat paper cup the sides of which, when it is being opened into a conical cup by pressure against the edges, will be more certain to arch away from each other instead of arching in the same direction than have such cups heretofore.

15 It is a further object of this invention to make a cup of the sort described in which the folds shall be unlikely to produce narrow corners when the cup is used for drinking.

20 It is a further object of this invention to provide a cup of the sort described in which creased or score marks shall locate the point at which the cup is to bend in the act of opening it.

25 Other and further important objects of this invention will be apparent from the disclosures in the accompanying drawings and in the specification.

30 The invention (in a preferred form) is illustrated in the drawings and hereinafter more fully described.

On the drawings:

Figure 1 is a view of one side of the cup.

35 Figure 2 is a view upon a smaller scale of the opposite side of the cup.

Figure 3 is a view upon the same scale as Figure 1, showing the top of the cup in its folded condition.

40 Figure 4 is a view of the blank from which the cup is made.

Figure 5 is a top plan view of the cup fully open.

45 Figure 6 is a top plan view of the cup partially open.

As shown on the drawings:

The cup is made from a blank having a curved edge 1 and a radial edge 2. The blank is approximately the shape of a sector 50 of a circle. The other radial edge of the sector, shown at 3, is not the edge of the blank but the blank continues beyond this edge to form a flap 4 having an edge 5, which is approximately radial. The end of 55 the flap 4 nearest the center of the curve 1

may have its edge in line with the radial edge 2 as shown at 6.

At the center of the curve 1 the blank is provided with a notch 7 of a general star-shape, the edges of the star being curved and convex toward the notch. The points of the star are in line with the proposed folds in the finished cup. One of these points is therefore in line with the line 3; the other is in line with the bisector 8 of the sector. 60 The lines 3 and 8 may correspond to actual physical structure of the blank, such as scoring, creases or the like, or they may be merely the proposed locations of the fold and the blank have no actual physical structure 65 corresponding thereto.

Two other lines 9 and 10 shown in Figure 4 correspond to actual physical structure. They may be score marks, creases or the like, creases being chosen for illustration in 70 Figure 3.

The point of the cup near the center of the curve 1 is to be folded against the wall of the cup, as shown at 12 in Figure 2. The fold 13 which produces this effect gives rise 80 to three short lines 14, 15 and 16, as seen in Figure 4. These lines are like the lines 8 and 3 as regards their correspondence to actual physical structure.

The space between the line 15 and the 85 notch 7 is approximately triangular and is covered with adhesive. One face of the flap 4 is also covered with adhesive, as shown in Figure 4. Preferably also the opposite face of the blank is covered with adhesive 90 over an area corresponding to the area between the line 15 and the point of the cup for securing the folded point 12 to the wall of the cup, as shown in Figure 2.

In making the cup from the blank the 95 first fold is along the line 8. This brings the edge 2 to coincide with the line 3. The second fold is along the line 3. This brings the adhesive covered face of the flap 4 against the outer face of the margin near 100 the edge 2. The folds along the line 8 do not intersect because the notch 7 has removed the material at the intersection. The point resulting from these two folds is rounded, as shown at 12 in Figure 2. The 105 final fold 13 of the cup is made after the seam between the flap 4 and the margin near the edge 2 has become firm. When this fold has been secured in place the cup is finished 110 and ready to be packed.

When the cup is to be used, the folded edges 3 and 8 are pressed toward one another. The creases 9 and 10 respond to this pressure sooner than the body of the material. Consequently, before this material flexes to any great extent elsewhere, the creases give rise to angles in the sides of the cup, as illustrated in Figure 6, in which the two triangular faces of the cup are plane and the two quadrilateral faces are slightly twisted owing to the fact that their upper edges are not in the same plane with the fold 13. When the pressure is continued to open the cup more fully, the twisted faces become markedly rounded, as shown in Figure 5, but the triangular faces continue to be nearly plane, or they may even become slightly concave.

A very slight pressure is sufficient to bring the cup from the flat form shown in Figure 3 to a form like that shown in Figure 6 because the natural tendency of the creases to make the paper flex at the lines 9 and 10 assists that pressure. A greater pressure is needed to complete the rounding of the cup because it must act to arch the material. If desired, the cup may be opened as far as slight pressure will open it and then filled. The weight of the water will then quickly bring the cup to its fully rounded form.

When the cup is brought to the fully rounded form, there are no sharp angles left near the folds 3 and 8 because of the effect of the creases 9 and 10 in insuring a portion of the wall of the cup being nearly plane and nearly tangent to the curved part of these folds. The upper edge of the cup, therefore, presents no place where it will not readily fit the mouth of the user in the act of drinking and the convenience of the cup is increased thereby.

I am aware that numerous details of construction may be varied through a wide range without departing from the principles of this invention, and I therefore do not 45 purpose limiting the patent granted otherwise than necessitated by the prior art.

I claim as my invention:

1. A foldable cup, comprising two sides each the shape of a truncated sector, each of 50 said sides having a single crease extending from points in the curved edge of the cup to opposite ends of said truncated edge, said sides when folded flat registering with each other.

2. A foldable paper cup, comprising two sides, each having approximately the shape of a circular sector with the point truncated, the truncating being done by folding said points against one side of the cup, each of 60 said sides having a single crease extending from the curved edge to opposite ends of said fold, the convex side of said crease being outward, said sides when folded flat registering with each other.

3. A foldable cup having a linear bottom, a triangular face terminating at each end of the bottom, and a quadrilateral face at each side of said bottom, said four faces constituting the walls of the cup, said triangular 70 faces when said cup is flattened lying upon opposite sides thereof, and said sides when folded flat registering with each other.

4. A flat folded cup, comprising two registering sides each the shape of a truncated 75 sector, said sides having creases extending from points in the curved edge of the cup to opposite ends of said truncated edge.

In testimony whereof I have hereunto subscribed my name.

CESARE BARBIERI.
